UNITED STATES PATENT OFFICE

ALBERT MASSÉ, OF BEAUPORT, QUEBEC, CANADA, ASSIGNOR OF TWENTY PER CENT EACH TO JOSEPH ALFRED EVERELL, MAURICE GRENIER, BOTH OF QUEBEC, AND ERNEST PLAMONDON AND UBALD FLOURDE, BOTH OF STE. ANNE DE BEAUPRÉ, CANADA

STREET OR STATION INDICATOR

Application filed July 13, 1925. Serial No. 43,336.

The present invention pertains to a novel street or station indicator designed particularly for use in a train of cars for the purpose of indicating the next stop in each car.

5 The principal object of the invention is the provision of a device of this character embodying a series of indicators, one in each car, so constructed and adapted that an inoperative unit is automatically concealed in order 10 that the passengers viewing this unit will not be deceived as to the position of the train.

The entire system is operated from any car in the train selected as the control car. The wiring of the apparatus is such that a defective unit will cause a current to flow to the pilot lamp in the control car in order to attract the attention of the operator. This centralized control constitutes another important object of the invention.

20 These objects are accomplished by providing in each unit a series of commutators designed to lead the current to one or the other of two signal lines when the movement of the indicator has ceased, and some of these commutators are also adapted to deliver current 25 from the signal lines to a signal magnet. In the normal operation of the device when the parts are in order, the connection between the active signal line and the commutator associated with the signal magnet is broken. At such times, one of the commutators is however connected to the inactive signal line. The commutators are moved in unison with the station display curtain, and when the curtain in a given unit fails to operate, the associated commutators will also fail to operate. The result is that the previously inactive signal line remains in contact with the commutator connected to the signal magnet, where- 35 by a circuit to the signal magnet is made when the device is operated for the next display.

A weighted blind is suspended over the display curtain and is released by operation of the magnet which is energized in the manner 45 described. At the same time, the movement of the blind is utilized to complete a circuit through the pilot lamp in the control car.

The invention is fully disclosed in the following description and in the accompanying 50 drawings in which:

Figure 1 is a front elevation of the sign operating units, one wall of the enclosed casing being removed;

Figure 2 is a section on the line 2-2 of 55 Figure 1;

Figure 3 is a section on the line 3-3 of Figure 1;

Figure 4 is a fragmentary plan view of Figure 1;

Figure 5 is a fragmentary plan section beneath the top wall of the casing; 60

Figure 6 is a wiring diagram of two connected units, the control switch of the initial left hand unit being closed while the switch in the right hand unit is opened; 65

Figure 7 is a perspective view of a curtain releasing mechanism embodied in each unit;

Figure 8 is a fragmentary transverse section taken through the casing;

Figure 9 is a fragmentary horizontal section through the mechanism shown in Figure 7, and 70

Figure 10 is an enlarged detail horizontal section through a portion of the structure disclosed in Figure 7. 75

Reference to these views will now be made by use of like characters which are employed to designate corresponding parts throughout.

Through the entire train of cars is run a series of conductors, namely, the positive main 1 which delivers current to the apparatus, the negative side being grounded, a bus line 2 which delivers current for operating the sign actuating mechanism in each car, signal lines 3 and 4 for conveying the current when the signs in the several cars are not in operation, and finally a signal bus conductor 5 for delivering current to the out-of-order signals associated with each unit. 85

With reference now to Figures 1 to 5, each car of the train contains a sign display and actuating device similar to that shown in the United States patent to Everell et al., No. 1,438,990 of December 19th, 95 1922. This device comprises a housing 6 having a pair of partitions 7 near its end walls in which partitions are journaled a pair of sign roller shafts 8 and 9. The shafts carry rollers 10 and 11 respectively 100

upon which is wound a flexible indicator sign 12 designating the various stops that the train makes and designed to wind from one roller to the other. The sign is illuminated by lamps 12' mounted within the 5 housing 6. These shafts further carry gears 10' and 11' which are connected through an intermediate pinion 13. The shaft 9 carries still another pinion 14 (Figure 3) meshing with a gear 15 mounted on a stub shaft 16 which is journaled in a suitable strip 17 secured within the casing 6. On the stub shaft 16 is also mounted a drum 18 containing a ratchet device of conventional form which carries the gear 15 when the drum is turned in a given direction and which moves independently of the gear when the drum turns in the opposite direction. From the drum extends a lever 19 adapted to work in a slot 20 cut in the upper wall of the housing.

On the top wall of the housing is mounted an air cylinder 21 lying parallel to the slot 20. The piston 22 in the cylinder is connected to a hook 23 which has a slot 24 in its free end for receiving the lever 19. The cylinder is fed from an air line 25. In each such line is contained an electro-magnetically operated valve 26 having one terminal 20 joined to the bus line 2 by a conductor 27, and the remaining terminal grounded as indicated by the numeral 28.

Adjacent each signal casing is mounted a control switch 29 having a pair of knife blades, one of which is connected with the main 1 through a conductor 30 and the other of which is grounded through a conductor 31. A pilot lamp 32 is connected in the ground line 31. The switch 29, is preferably formed with an insulating handle 29', the purpose of which will be later described. The switch blades are operable to engage contacts 34 and 34', the contact 34' being joined to a signal bus conductor 5 by a wire 33, while the opposed contact 34 is connected to an automatic indicator switch 36 through the conductor 35. The switch 36 is operable to engage a pair of spaced contacts 37 and 38, the contact 37 being connected by a wire 39 to the bus line 2, while the contact 38 is connected to another portion of the apparatus, as will be herein-after indicated. The switch 36 is operated by means of an electro-magnet 40 electrically connected between the conductor 35 and a ground connection 41. A hand operated switch 42 is disposed between the magnet 40 and the ground for controlling the operation of the switch 36.

60 In the operation of the device, as thus far described, a particular car in the train is selected as the control car from which the indicators in all the cars are operated. In the control car the switch 29 is closed as 65 initially shown in Figure 6, and the hand

switch is operated at each station. In the remaining cars the current switch 29 and hand switch 42 are left open as in right of Figure 6, but the indicators in these cars nevertheless operate through the manipulation of the switches 29 and 42 in the control car. The switch 29 in the control car is normally closed to furnish current from the main 1 to the several indicators whenever the hand switch 42 is closed. Upon reaching a station, the switch 42 is closed whereby the electro-magnet 40 carries the indicator switch 36 to the contact 37. The current thence flows through conductor 39 to the bus line 2 and from there to each of the magnetic valves 26 of the several cars. Air is thus supplied to each cylinder 21 whereby the gear 15 in each casing is turned. This gear rotates the corresponding pinion 14 whereby the curtain rollers 10 and 11 are also turned to shift the sign 12. When the station has been passed, the switch 42 in the control car is again opened whereby electro-magnet 40 is de-energized and the indicator switch 36 returned to the contact 38. The discontinuation of current in the bus line 2 closes the valves 26 and stops the flow of air to the cylinders 21. Each piston 22 is returned by means of a spring 43 attached to the corresponding lever 19 and to a fixed point within the casing 6. Due to the above mentioned ratchet 18, the return movement of the lever does not affect the gearing. The return of the pistons is permitted by means of check valves disposed therein in a manner well known in the art.

Behind the sign rollers, with reference to the sight opening 44 of the casing 6 (Figure 2), are journaled a pair of parallel commutator shafts 45 and 46 supported in suitable bearings 45^a and 46^a. The shafts are connected by equal engaging gears 45' and 46', which are twice the circumference of the gear 11' which meshes with the gear 45'. The shaft 46 carries a pair of commutator drums 47 and 48 carrying diagonally opposed brushes 47^a, 47^b and 48^a, 48^b. The brushes on each commutator are connected by wires 49 running through the drums. Similarly, the shaft 45 carries a pair of commutator drums 50 and 51 each having a pair of diagonally opposed brushes 50^a, 50^b, and 51^a, 51^b connected by wires 52. The drums on each shaft are oppositely disposed to one another with reference to the position of their brushes, and the adjacent commutators on different shafts are parallel, as shown in Figure 5. Double contacts 53 and 54 are placed between the shafts 45 and 46, and single contacts 55, 56, 57 and 58 are placed outside the shafts. These contacts are so arranged as to engage the brushes of one pair of diagonally opposite commutators, one commutator on each shaft, and to maintain the remaining commutators disengaged in any position of the parts. Due to

the relation in the size of the gears 11', 45' and 46' each rotation of the roller 11, which is sufficient to bring a new legend into view, causes a half turn of the shafts 45 and 46. Consequently, the engaged commutators are alternated from one diagonal pair to the other.

In the normal operation of the device after the indicator switch 36 has been returned to the contact 38, the current flows along a conductor 60 which is branched to the contacts 55 and 56. Return lines 61 and 62 connect the intermediate contacts 53 and 54 respectively to the signal lines 3 and 4 respectively. In one of the two possible positions of the commutators, when the pair 48 and 50 are engaged (Figure 6) the current continues from the contact 56 across the commutator 48 to the intermediate contact 54 and thence through the return 61 to the signal line 3. No current is supplied to the other engaged commutator 50 since the contact 53 is disconnected from the commutator 47. In the other position of the commutators, when the pair 47 and 51 are engaged, as in right hand portion of Figure 6, the current continues across commutator 47 to the return 62 and to the line 4. No current is supplied to the other engaged commutator 51 when the parts are in proper working order, since the contact 54 is disconnected from the commutator 48.

Each casing 6 contains a box 63 enclosing an electro-magnet, the plunger 64 of which is slidable through one of the walls of the box. Into one end of the box are passed a pair of guide screws 65 on which is mounted a slotted slide 66 as shown to advantage in Figure 10 consisting of insulating material. To the sides of the box are attached a pair of metallic strips 67 and 68 insulated from said box by insulating strips 68' and held in place by bolts 69 passed through the box. To the ends of the block 66 are secured a pair of contacts 70 and 71 disposed between the strips 67 and 68 and so spaced that only one of the contacts can engage a strip at a time. An insulating bushing 72 surrounds the bolt 69 within the strip 68. The electro-magnet (73 shown in Figure 9) within the box has one of its terminals connected to a post 73 on the strip 68 and the remaining terminal connected to the bolt 69 which is grounded through a conductor 74. To the contact 71 is attached a conductor 75 which is branched at 75^a and 75^b Figure 6 and thus joined to the contacts 57 and 58. The strip 67 has attached thereto a post 76 to which is connected the main 1. A conductor 77 connects the contacts 70 to the signal bus conductor 5.

Adjacent the contact 71 and plunger 64 is journaled a curtain control shaft 78 carrying a pinion 79 shown in Figure 5. In parallel relation to this shaft is journaled a curtain roller 80 on which is wound a curtain 81 passing through a slot 82 in the top of the hous-

ing 6 and over rollers or guides 83 to the front wall of the housing. The free end of the curtain carries one or more weights 84 by means of which the curtain may be drawn over the sight opening when the roller 80 is released. The roller is normally held against rotation by means of a pinion 85 mounted thereon and meshing with the pinion 79, the shaft 78 of the latter pinion carrying a detent 86 normally engaging the projecting plunger 64. Opposite the contact 71, the shaft 78 carries a finger 87 adapted to engage this contact but spaced therefrom when the detent is held by the plunger. A spring 88 secured to the base of the casing 6 engages one end of the plunger 64 and normally holds it projected in the positions shown in Figures 9 and 8.

It has already been explained that the current after passing through the apparatus in the control car is led to one of the signal lines 3 and 4. The active signal line is disconnected from the signal magnet at 50 or 51. By reason of the direct connection between the sign roller and the commutators, the members 50 and 51 which are adapted to connect with the branches 75^a and 75^b, are separated from the active return line 61 or 62 when the apparatus is in proper order.

In the right hand portion of Figure 6 is illustrated the position of parts in one of the non-control units when this apparatus is out of order. The signal line 3 is the active carry off line. Due to a defect in the mechanism, the sign roller did not operate at the previous station and consequently the commutators have also failed to move. Therefore, the connection between the active return line 61 and the commutator 51 has not been broken. The current then flows from the active signal line 3 through the line 61, commutator 51, branch 75^b, line 75, arm 71, strip 68, terminal 73, through the magnet within the box 63, through bolt 69 and ground wire 74. The magnet within the box is therefore energized and withdraws the plunger 64. The detent 86 is thus released, and the weights 84 at the end of the line 81 are free to turn the roller 80, which motion is imparted to the shaft 78. The finger 87 engages the arm 71 and moves the slide 66 whereby the arm 70 engages the strip 67 and the magnet circuit is broken. This strip is connected to the main 1 at terminal 76 and the main current consequently flows along arm 70, conductor 77, signal bus conductor 5, line 33 of the control car, switch terminal 34' through the blade of the control switch 29 which is normally closed and finally through the pilot lamp 32 in the control car to the ground. Thus, the pilot lamp in the control car where the operator stands is illuminated when any unit becomes inoperative, but the pilot lamps in the remaining cars receive no current since the corresponding control switches are normally open. It is to be noted, that no cur-

rent can flow directly from the main 1 and through the switch 29 of any car to the pilot lamp because the handle 29' between the blades of each switch is of insulating material.

5 While a specific embodiment of the invention has been illustrated and described, it is to be understood that various alterations in the details of construction may be made without departing from the spirit of the invention 10 as indicated by the appended claims.

Having thus fully described the invention, what I claim as new and desire to protect by Letters Patent is:—

15 1. In a station indicator system, a plurality of signals having changeable station indicators, mechanism mounted in the signals for actuating the said indicators, means for simultaneously operating the said indicator actuating mechanism, means carried by said signals operable to conceal the indicators, and means for actuating the signal covering means of any signal to conceal the same when the indicator actuating mechanism fails to operate.

20 2. In a station indicator system, a plurality of signal casings having changeable station indicators mounted therein, mechanism mounted in the casings for actuating said indicators, means for simultaneously operating the indicators from a control unit, means operable to cover the indicators mounted on said casings, and means for actuating the said signal covering means of any signal whose indicator actuating mechanism fails 25 to operate in harmony with the remaining indicators.

30 3. In a station indicator system, a plurality of signals including signal casings and station indicators mounted in the casings, mechanism mounted in each casing for actuating said indicators in step by step movement, electrically controlled means for simultaneously operating the said signal actuating mechanisms, means carried by each casing operable 35 to conceal the indicator thereof at certain periods, and means for actuating the indicator covering means of any signal whose indicator actuating mechanism fails to operate in harmony with the remaining indicators.

40 4. In a station indicator system, a plurality of signals including signal casings and station indicators mounted in the casings, mechanism mounted in each casing for actuating said indicators in step by step movement, electrically controlled means for simultaneously operating the said signal actuating mechanism, means carried by each casing operable to conceal the indicator thereof at certain periods, and means operatively associated with the 45 electrically controlled actuating means for actuating the covering means of any signal when the indicator thereof fails to operate in conjunction with the remaining indicators.

45 5. In a station indicator system, a plurality of signals having changeable station indica-

tors, mechanism mounted in each signal for actuating the said indicators, means for simultaneously operating the said indicator actuating mechanisms, means carried by said signals for concealing the indicators at certain periods, and means for actuating the said signal covering means to conceal the signal whose indicator operating mechanism fails to function.

70 6. In a station indicator system including a plurality of signals having changeable station indicators, mechanism mounted for actuating each of said indicators, electrically controlled means for simultaneously operating the indicator actuating mechanism, a curtain operable to conceal each indicator, mechanism for actuating the curtains to signal concealing position, and electrically operated mechanism operatively associated with the electrically controlled indicator mechanism operating means for concealing an indicator whose operating mechanism fails to operate in conjunction with the remaining indicators.

75 7. In a station indicator system, the combination with a plurality of signals having changeable station indicators, mechanism operable to actuate the indicators in a step by step movement, and electrically controlled means for simultaneously operating the said indicator actuating mechanisms, of curtains mounted on the signals operable to indicator concealing positions, curtain operating mechanism operatively associated with the indicator actuating mechanism, and means for operating the curtain of any signal to conceal the indicator thereof when the indicator actuating mechanism fails to operate in conjunction with the remaining indicators.

80 8. In a station indicator system, the combination with a plurality of signals having changeable station indicators, mechanism operable to actuate the indicators in a step by step movement, and electrically controlled means for simultaneously operating the said indicator actuating mechanisms, of curtains mounted on the signals operable to indicator concealing positions, curtain operating mechanism operatively associated with the indicator actuating mechanism, and electrically operated means operatively associated with the electrically controlled indicator mechanism operating means for actuating the curtain of any signal to indicator concealing position when the actuating mechanism of said indicator fails to operate in conjunction with the remaining indicators.

85 In witness whereof I have hereunto set my hand.

ALBERT MASSE.
